UNITED STATES PATENT OFFICE.

CHARLES CROMPTON, OF WORCESTER, MASSACHUSETTS.

BROKEN-PICK EXTRACTOR FOR LOOMS.

1,319,759.

Specification of Letters Patent. Patented Oct. 28, 1919.

Continuation of application Serial No. 108,197, filed July 8, 1916. This application filed July 16, 1918.
Serial No. 245,202.

To all whom it may concern:

Be it known that I, CHARLES CROMPTON, a citizen of the United States, and a resident of Worcester, in the county of Worcester and State of Massachusetts, have invented an Improvement in Broken-Pick Extractors for Looms, of which the following description, in connection with the accompanying drawings, is a specification, like characters on the drawings representing like parts.

This application is a continuation of my co-pending application Serial No. 108,197, filed July 8, 1916.

15 This invention relates to looms for weaving fabrics and the like and particularly to means for extracting a broken partial or incomplete pick from the shed of the warp in looms of the above character.

20 The object of my present invention is the provision of means arranged to enter the open shed of the warp, and after the filling pick has been passed through said shed, should said pick become broken or 25 be incomplete through exhaustion to remove said broken or incomplete pick from said shed.

With this and other objects in view my invention consists in a novel combination 30 and arrangement of parts hereinafter described and more specifically pointed out in the appended claims.

In the accompanying drawings I have shown my invention combined with a portion 35 of a loom sufficient to enable those skilled in the art to understand the construction and operation thereof.

Referring to the drawings:

Figure 1 is a transverse section of a portion 40 of a loom embodying my improvements;

Fig. 2 is a plan view of Fig. 1, in this view the loom frame and some of the parts are omitted;

Fig. 3 is a detail front view of my improved broken pick extractor;

Fig. 4 is, on an enlarged scale, a sectional detail of the upper portion of the extracting members;

Fig. 5 is a view corresponding to Fig. 4, 50 but shows the plunger in a different position;

Fig. 6 is a view similar to the upper part of Fig. 3 but representing the tubes as having their openings or slots directed downward; and

Fig. 7 is a view similar to Fig. 4, but representing a set screw constituting additional means for securing the tube in any adjusted position upon its support.

In the accompanying drawing 10 is the loom frame, 11 is the breast beam having, in this instance, a filling fork indicating mechanism 12.

13 is the usual lay sword having the lay beam 14 and hand rail 15 secured thereto, 65 and 16^a is the shuttle having the filling 16 contained therein.

17 are the warp threads and 18 is the woven fabric.

The above described parts are or may be 70 of the usual and well known type.

I will now describe my improved pick extracting device as combined with the above mentioned parts.

In this instance I have provided a vertical 75 member 19, the upper end 19^a of which has slidably mounted therein a plunger 20, said plunger 20 having an opening 21 which extends upwardly from the lower end of said plunger 20 and connects with an opening 80 22 which extends from said opening 21 to the periphery of said plunger 20.

The upper portion 19^a of the member 19 has a tapering projection 19^b to which is secured, in this instance, a tube 23, the longitudinal wall of which has a horizontal opening 24 therein. Said tube 23 has a driving fit upon its projection 19^b and can be turned or adjusted by a wrench or otherwise so as to direct the slot or opening 24 90 in any direction throughout 360°. If desired both tubes 23 may be positioned with their slots 24 directed downward, thereby very effectively to insure the sucking in of both parts of a broken pick, one at each 95 end of the lay. If at each end of the lay the slots 24 be directed toward the fell of the cloth, I insure the sucking in of the pieces of the broken or incomplete pick which lies at that side of the loom from 100 which said pick is laid, and in certain cases, with such positioning of the slots, the other piece may also be sucked in, depending upon the character of the filling and the degree of suction and the width of the slot.

The projection 19^b, of the member 19, has an opening 25 therein which co-operates with the opening 22 of the plunger 20 (see Fig. 5).

The member 19 is pivotally secured at 26 110

to a stand 27 secured to the floor, said stand 27 having a horizontally extending arm 28 to which is pivotally connected, one end of a connecting rod 29, the opposite end of said connecting rod 29 being pivotally connected to a collar 30 secured to the lower portion of the plunger 20.

Secured to the lower end of the plunger 20 is one end of a flexible tube 31, the opposite end of said tube 31 being secured to a vacuum tank (not shown) which may be of any suitable and well known construction.

I have only described one of the devices 15 as the opposite device is of like construction, the two devices being retained in their inner operative positions by means of a spring 32 extending between the two devices.

I will now briefly describe the operation 20 of the above mentioned parts.

If the filling 16 should become broken while being passed through the open shed of the warp 17, see Fig. 2, the tube 23 being inserted in its operative position, and the 25 plunger 20 being in its upper position with the opening 22 coöperating with the opening 25, thus causing a vacuum to be produced in the tube 23, the broken end of the filling will be carried through the tube 23 and thus 30 through the openings 25 and 22 into the opening 21 in the plunger 20 before the forward beat of the lay.

On the forward beat of the lay the cams 33 secured to the lay beam 14, will engage 35 the members 19^a, causing said members to be moved outwardly as shown by broken lines Fig. 3.

As the members 19^a are moved outwardly 40 the plunger 20, through the connectors 29, will be caused to move downwardly, thus closing the openings 22 and 25, see Fig. 4.

As the plunger 20 is carried downwardly the filling end will be severed by the edges 45 of the openings 22 and 25.

I have shown the filling fork mechanism 50 mounted on the breast beam, but if desired the filling fork mechanism may be mounted on and operated by the lay in any of the usual and well known ways.

In Fig. 6, I have represented the tubes 55 23 as having their slots 24 turned downwardly. The said slots may in any event be of any desired width.

In Fig. 7, I have represented one of the 60 tubes 24 as secured with a driving fit upon the nipple or projection 19^b and have represented a set screw 23' constituting additional means for securing the tube upon said nipple or projection and received in a transverse slot 23'' in said tube. The tubes 65 23 are held, because of the driving fit, securely upon the projections 19^b against all liability of falling off under the impact of the lay, and yet with capacity for rotative adjustment, as by the application of a hand

wrench or in any other suitable manner. Said set screws provide merely additional securing means.

It will be evident that, particularly if both the slots 24 be directed downward, 70 both ends of the broken pick will be sucked into the tubes 23, and if an incomplete pick be laid, it will be sucked in at that side of the loom from which it is laid. In certain cases and in certain positions of the slots 75 24, it may not be necessary or worth while to suck in the end of the broken pick which is at that side of the loom occupied by the shuttle just after laying the broken pick; that is, at the left hand side of the loom, 80 viewing Fig. 2.

It will readily be seen and appreciated by those skilled in the art that I have provided a simple and efficient device for removing 85 a broken pick from the open shed of the warp without the necessity of stopping the loom. The uprights or members 19 are in practice preferably made of tempered steel, and this fact, together with the play in the joints or pivotal points 26 gives ample 90 springing facilities when the lay hits the tubes 23 after the latter are withdrawn from the ends of the shed by the cams 33. Thus in practice the lay serves properly to beat up the filling at the fell of the cloth 95 and the tubes 23 with their supports yield sufficiently for this purpose.

Having thus described my invention, it will be evident that many changes and 100 modifications may be made therein by those skilled in the art without departing from the spirit and scope thereof, therefore, I do not wish to be limited to the specific details herein disclosed, but what I claim is:

105

Claims:

1. A loom having a shuttle, picking means to lay the filling of said shuttle in the shed of the loom, and means to withdraw from the shed laterally of the loom before heat-up, that end of a broken or incomplete pick 110 which lies at the side of the loom from which such pick was laid.

2. A loom having a shuttle, picking means to lay the filling of said shuttle in the shed of the loom, and means to withdraw, intact 115 from the shed before beat-up, that end of a broken or incomplete pick which lies at the side of the loom from which such pick was laid.

3. A loom having a shuttle, picking means to lay the filling of said shuttle in the shed of the loom, and means to withdraw, intact 120 from an end of the shed before beat-up, that end of a broken or incomplete pick which lies at the side of the loom from which such pick was laid.

4. A loom having a shuttle, picking means to lay the filling of said shuttle in the shed of the loom, and means to enter the end of 125 the shed before beat-up and to withdraw 130

that end of a broken or incomplete pick which lies at the side of the loom from which such pick was laid.

5. A loom having a shuttle, picking means 5 to lay the filling of said shuttle in the shed, and means to withdraw from the shed before beat-up the two ends of the broken pick each intact.

6. A loom having a shuttle, picking means 10 to lay the filling of said shuttle in the shed, and withdrawing means adapted to enter the end of the shed before beat-up and to withdraw therefrom the two ends of the broken pick.

15 7. A loom having a shuttle, picking means to lay the filling of said shuttle in the shed, and broken pick withdrawing means, and means to operate the same before beat-up of the lay to withdraw a broken pick as an entity.

20 8. A loom having a lay, and a shuttle, picking means to lay the filling of said shuttle in the shed, and a broken pick extractor distinct from and independent of the lay to withdraw a broken pick, and means to operate said extractor to extract a broken pick before the beat-up.

25 9. A loom having a shuttle, a lay, and

picking means to lay the filling of a shuttle in the shed, and pneumatic means to withdraw the two ends of the broken pick in a substantially horizontal direction from the shed before beat-up. 30

10. A loom having a shuttle, picking means to lay the filling of said shuttle in the shed of the loom, and means to withdraw from the shed laterally of the loom, before beat-up the two ends of a broken pick. 35

11. A loom having a shuttle, picking means to lay the filling of said shuttle in the shed of the loom, and means to withdraw from the ends of the shed before beat-up, the two ends of a broken pick. 40

12. A loom having a shuttle, operating means to lay the filling of said shuttle in the shed of the loom and means to withdraw before beat-up an intact broken or partial pick from within the shed, whereby said broken pick already laid into the shed is actually 45 withdrawn from within the shed as an entity. 50

In testimony whereof, I have signed my name to this specification.

CHARLES CROMPTON.

It is hereby certified that in Letters Patent No. 1,319,759, granted October 28, 1919, upon the application of Charles Crompton, of Worcester, Massachusetts, for an improvement in "Broken-Pick Extractors for Looms," an error appears in the printed specification requiring correction as follows: Page 2, lines 109-110, claim 1, for the compound word "heat-up" read *beat-up*; and that the said Letters Patent should be read with this correction therein that the same may conform to the record of the case in the Patent Office.

Signed and sealed this 7th day of June, A. D., 1921.

[SEAL.]

KARL FENNING,

Acting Commissioner of Patents.

Cl. 139—18.
